UNITED STATES PATENT OFFICE.

WILLIAM P. THOMSON, OF LANSDOWNE, AND SAMUEL G. THOMSON, OF ALTOONA, PENNSYLVANIA.

JOINT FOR RAILWAY-RAILS.

No. 831,579.

Specification of Letters Patent.

Patented Sept. 25, 1906.

Application filed February 20, 1905. Serial No. 246,394.

To all whom it may concern:

Be it known that we, WILLIAM P. THOMSON, of Lansdowne, Delaware county, and SAMUEL G. THOMSON, of Altoona, Blair county, Pennsylvania, have invented a new and useful Joint for Railway-Rails, of which the following is a full, clear, and exact description, reference being had to the accompanying drawings, forming part of this specification, in which—

Figures 1 to 8 show different forms of joint constructed in accordance with our invention.

Our invention relates to the class of rail-joints wherein splice-bars or angle-bars are used, and is designed to increase the stiffness of the joints, lessen the battering of the rail ends, and provide chafing-bars which may be renewed at small cost, while retaining the outer bars, bolts, &c.

The invention consists in providing two bars on each side of the rail at the joint, these bars being separable, so that one may be retained and the other replaced.

The invention may be applied to splice-bars either with or without depending flanges, though we prefer to employ said flanges. It may also be used with the two bars of the same length on the same side or with one bar of greater length than the other.

In the drawings, referring to Fig. 1, 2 is the head, 3 the web, and 4 the base-flanges of the rail. The angle-bar proper is preferably provided with a head 5, a downwardly and outwardly inclined or curved web 6, an outer base-flange 7, and an inner base rib or flange 8. It is also preferably provided with a depending flange 9, arranged to extend below the rail-base, this being curved to present a concave inner face in the form shown and having an edge rib or head 10. In this form the other bar of the pair is of channel shape, having a narrow upper flange 11, a web 12, and an outwardly-extending tapered base-flange 13, extending between the base of the outer bar and the base-flange of the rail. The securing-bolt 14 is preferably provided with inclined washers 15, arranged to fit the inclined bolting-faces of the outer bars and allow bolts to be used with the ordinary head and nut. The bolt-head may be formed to fit the face of the outer bar, if desired.

In Fig. 2 we show a similar form, except that the flanges 9^a are reversely bent or cor-

rugated and the base-flanges 13^a of the channels or inner bars are not tapered. The heads 5^a are also of slightly different shape, and the bolt is shown with a head arranged to fit upon the outer curved bolting-face of the outer bar.

In the form of Fig. 3 the flanges 9^b extend downwardly in substantially vertical planes, and the webs 6^b of the outer bar are inclined outwardly at a greater angle to merge directly into the flanges 9^b.

In the forms of Figs. 4 and 5 the inner bars or chafing-irons are provided with thickened upper heads or flanges 11^c and with inner base ribs or flanges 16. In this form the outer base-flanges 13^c of the inner bars are cut away for the intermediate portion of their length between the ties to receive the outer bars. The end portions of the flanges 13^c extend over the ties 17. In this form the depending flanges 9^c of the outer bars are shown as inclined inwardly toward each other.

In the form of Fig. 6 the depending flanges 9^d are formed as a part of the inner bars or chafing-irons and extend from the outer flanges 13^d of such irons. In this form the base flanges or portions 7^d of the outer bars rest upon the flanges 13^d of the inner bars, and the intermediate portions of the outer bars afford vertical bolting-faces.

In the form of Fig. 7 the flanges 13^e of the inner bars are cut away through the intermediate portions of their length sufficiently to allow the flanges 7^e of the outer bars to rest directly upon the flanges 4^e of the rail-base. In this form also the bolting-faces extend vertically.

In the form of Fig. 8 the inner irons are in the form of channels with outer base ribs or flanges 13^f, which are narrow throughout their length and allow the base-flanges 7^f of the outer irons to rest upon the base-flanges of the rail throughout the length of the two irons. In this form also the bolting-faces are vertical. Types, as shown by Figs. 1 to 4, may also be made with vertical bolting-faces.

The advantages of our invention result from the use of the two bars on each side of the joint. This gives the required stiffness with the use of light sections and lessens battering of the rail ends caused by excess amount of metal in the joint-bars. The con-

struction is of great advantage in this regard where the depending flanges are not used. By varying the thickness and form of the inner bar the same section of outer bar may be used on rails of different forms and sizes. The inner bars carry the chafing and wear and may be renewed at slight cost, thus allowing the outer bars and attachments to be used indefinitely. The use of the two bars enables both of them to extend over the ties, while if a depending flange is used it may be sheared off to clear the ties, or either bar may be made of short length to terminate at the adjacent edges of the ties and with or without a depending flange. In such case the inner bar may be made of such length as to give the desirable bolting capacity, while the outer bar may be made of shorter length to reinforce the central portion of the joint. Both bars may also be cut off, so that they both terminate at the adjacent edges of the ties, thus giving a very rigid short joint. In the long form of joint the lower flange of the inner bar may extend beyond the edge of the rail-base to contain spiking-slots over the ties, while the part between the ties may be sheared off to allow the depending flange of the outer bar to extend down around the foot of the rail. The depending flange may be used either on the inner or outer bar, as desired. The depending flange may be straight or curved or may be omitted altogether, neither bar extending below the rail-base. By using a tapered lower flange on the inner bar the outer bar may be made of heavier section where it joins the depending flange, thus increasing the strength. By the word "inclined" in the claims we intend to cover a bolting-face which is either straight-inclined or curved, either of which performs the same function.

Many changes can be made in the form and arrangement of the two bars without departing from our invention. Although we only show these bars in the drawings in connection with the ordinary T-rail, we intend to cover the same as applicable to any type of rail, especially girder or street-car rails.

We claim—

5. A pair of coacting splice-bars arranged to fit upon one side of a rail-joint one of said splice-bars being longer than the other; substantially as described.
6. A pair of coacting splice-bars arranged to fit upon one side of a rail-joint, one of said bars having a flange arranged to depend below the rail-base; substantially as described.
7. A rail-joint having two coacting bars on each side thereof one of each pair of the bars being longer than the other of such pair; substantially as described.
8. A rail-joint having two coacting bars on each side thereof, one of each pair having a flange depending below the rail-base; substantially as described.

5. A pair of coacting splice-bars arranged to fit one side of a rail-joint, the inner bar being shaped to fit the fishing-angles of the rail and to stand free from the rail-web to allow inward adjustment for wear; substantially as described.

6. A pair of coacting splice-bars arranged to fit one side of a rail-joint, the outer bar having an inclined bolting web-face, one of said bars being longer than the other; substantially as described.

7. A pair of coacting splice-bars arranged to fit on the side of a rail-joint, the inner bar having an upper flange or head arranged to stand free from the web of the rail to provide for adjustment and fit between the head of the rail and the upper end of the outer bar, said inner bar having a lower flange or rib arranged to rest on the base-flange of the rail through at least a portion of the length of said bar-flange; substantially as described.

8. A pair of coacting splice-bars, arranged to fit one side of a rail-joint, the inner bar being cut away at its base for a portion of its length to receive the outer bar; substantially as described.

9. A rail splice-bar of uniform channel-section having its web adjacent to the web of the rail, the flanges projecting outwardly and fitting the fishing-angles of the rails, and the lower flanges diminishing in thickness outwardly for their entire width; substantially as described.

10. In a rail-joint the combination of one splice bar or plate fitting into or against another splice bar or plate on the same side of the rail, of which one or both of said plates have an inclined web portion through which the bolts pass said web portions being spaced apart from each other; substantially as described.

11. In a rail-joint, the combination of one splice bar or plate fitting into another splice bar or plate on the same side of the rail, at least one of said bars or plates having a depending flange to extend below the base of the rail, substantially as described.

12. In a rail-joint, the combination of one splice bar or plate fitting into another splice bar or plate on the same side of the rail, at least one of said bars or plates having an inclined bolting member and a depending flange extending below the base of the rail; substantially as described.

13. In a rail-joint, the combination of one bar fitting into another bar, which in turn stands free from the web of the rail and fits the fishing-angles of the head and foot to provide for adjustment toward the web of the rail; substantially as described.

14. In a rail-joint the combination of a bar having an inclined bolting-web and a channel-bar into which the outside bar fits, substantially as described.

15. In a rail-joint the combination of a bar

having a flange depending below the foot of the rail from the outer edge of its foot member, and a channel-bar into which said bar fits; substantially as described.

5 16. In a rail-joint the combination of a bar having an inclined bolting member and having a depending flange extending below the rail-base from the outer edge of its foot member, and a channel-bar into which said outside bar fits; substantially as described.

15 17. In a rail-joint, the combination of a bar having an inclined bolting-face and having a flange depending and extending inward under the rail-base from the outer end of the foot member of said bar, and a channel-bar into which the outside bar fits, substantially as described.

20 18. In a rail-joint, the combination of a bar having an inclined bolting-face and having a head or stiffening-ribs on the lower end of a depending flange, which said flange extends below the rail-base from the outer edge of the foot member of said bar, and a channel-bar into which the outside bar fits.

25 19. In a rail-joint the combination of a bar having an inclined bolting-face, and having a head or stiffening-ribs on the lower end of an inwardly-depending flange extending below and under the base of the rail from the outer edge of the foot member of said bar, and a channel-bar into which the outside bar fits, substantially as described.

30 20. In a rail-joint, the combination of one bar fitting into a longer bar of channel-section provided with flanges tapered for their entire width; substantially as described.

35 21. In a rail-joint, the combination of one bar fitting into another bar of a channel-section having one or both of its flanges tapered, said outside bar having a flange depending below the base of the rail from the outer end of its foot member.

40 22. In a rail-joint, the combination of one bar fitting into another bar of channel-section, and having one or both of its flanges tapered, said outside bar having a depending flange extending inward under the rail-base from the outer end of its foot member.

45 23. In a rail-joint, the combination of one bar fitting into another bar of a channel-section having one or both of its flanges tapered, said outside bar having a head or stiffening-ribs on the lower end of a depending flange extending from the outer end of its foot member; substantially as described.

50 24. In a rail-joint the combination of one bar having a top head which fits under the top flange and abuts against the vertical web of a channel-bar, while the foot member of

said outside bar fits over the bottom flange, 60 but stands free of the vertical web of said channel-bar, substantially as described.

25 25. In a rail-joint, the combination of one splice bar or plate fitting another splice bar or plate of greater length; substantially as 65 described.

26. In a rail-joint, the combination of two splice-bars on the same side of the rail, the inside bar fitting the fishing-angles of the rail, and being of greater length than the outside 70 bar; substantially as described.

27. In a rail-joint, the combination of two splice-bars on the same side of the rail, the inside bar being the longer and extending over the ties, while the outside bar is comparatively short and has a depending flange extending below the base of the rail between the ties; substantially as described.

28. In a rail-joint the combination of two splice-bars on the same side of the rail, the inside bar fitting the fishing-angles of the rail and being of greater length than the outside bar which fits into it and has a depending flange extending below the base of the rail between the ties; substantially as described. 85

29. In a rail-joint the combination of two splice-bars on the same side of the rail, the inside bar fitting the fishing-angles of the rail and being of greater length than the outside bar which fits against it and has a depending flange extending inward and under the base of the rail between the ties; substantially as described.

30. A pair of coacting splice-bars arranged to fit on one side of a rail-joint, the outer bar 95 having the part through which the bolts pass provided with an inclined outer bolting-face, and said outer bar being out of contact with the under side of the rail-base; substantially as described.

31. A pair of coacting splice-bars arranged to fit on one side of a rail-joint, the outer bar having a slanting portion through which the bolts pass, said slanting portion being inclined on its outer face and said outer bar being free from contact with the under side of the rail-base; substantially as described.

In testimony whereof we have hereunto set our hands.
